Patented Feb. 21, 1922.

UNITED STATES PATENT OFFICE.

WILLIAM H. STOREY, OF ENSLEY, ALABAMA, ASSIGNOR OF ONE-HALF TO SAMUEL C. MATTHEWS AND ONE-HALF TO EDWARD G. SCHEUERMAN AND JOHN M. FOX, ALL OF ENSLEY, ALABAMA.

FOLDING TOY BED.

1,407,284.

Specification of Letters Patent. Patented Feb. 21, 1922.

Application filed April 11, 1921. Serial No. 460,226.

To all whom it may concern:

Be it known that I, WILLIAM H. STOREY, a citizen of the United States of America, residing at Ensley, in the county of Jefferson, son, and State of Alabama, have invented certain new and useful Improvements in Folding Toy Beds, of which the following is a specification.

My invention relates to a toy bed adapted to fold and which is characterized by the distinctive manner in which the side members are hinged to the posts of the head and foot, and by the manner in which the mattress supporting frame will effectively brace and clamp the bed in its operative position.

It is particularly my object to avoid any parts which will work loose or which will rattle or provide a flimsy or insecure bed, and to this end the side members are permanently hinged to the posts of the head or foot so as to turn about the latter as axes, thus permitting the head and foot to be collapsed by a lateral lazy tong movement and therefore requiring no displacement or removal of any part of the bed frame proper and especially requiring no tools for assembling or collapsing the bed.

A further distinctive feature of my invention is the provision of the mattress support in the form of a rectangular frame which by engagement with the bed sides will securely clamp and hold them in rectangular relation to the head and foot and thus provide a firm, secure and anti-rattling bed brace.

A further object of my invention is to construct the bed from both wire and metal strips, the latter forming the sides of the bed and the bracing mattress support which has spring loops that tightly clamp the side bars.

My invention will be better understood by the exemplification thereof shown in the accompanying drawings, in which:

Fig. 1 shows the bed in assembled position in perspective view.

Fig. 2 is a plan view on a smaller scale of the bed in collapsed or folded position, the mattress support having been removed.

Fig. 3 is a detail cross sectional view through one of the sides to illustrate the character of the clamp attachment of the mattress supporting and bracing frame thereto.

Fig. 4 is a sectional view taken on the line 4—4 of Fig. 3.

Similar reference numerals refer to similar parts throughout the drawings.

In the embodiment illustrated, I show the head and foot of the bed made of wire and each comprising upright side posts 1 and 2, which are cross connected overhead by a wire 3 and below by the spaced wires 4 and 5, the cross wires 3 and 4 being connected at intervals by vertical wires 6. All wires at their point of junction are suitably and positively engaged so as to form a rigid rectangular head or foot frame for the bed, but it is to be understood that my invention is not confined to any design of head or foot members for the bed nor to the character of material from which they are formed. The corresponding side posts 1 and 2 of the head and foot are respectively connected by metal side bars 7, the ends of which are bent about posts to form the hinge eyes or loops 8. The side bars are of such a width as to fit closely between the cross wires 4 and 5 which thus form bearings to prevent vertical displacement of the bar loops 8 on their respective posts. With the bed frame proper thus manufactured and assembled, it will be evident that each side bar will hinge about the posts 1 or 2, to which it is respectively connected, and will thus permit the bed frame proper to be collapsed and folded by a relative lateral shifting or lazy tongs movement of head and foot until the bars become practically superimposed on each other. This position of the collapsed and folded bed is shown in Fig. 2, which is the position in which it is shipped.

To brace the bed in its operating position and to support the mattress, not shown, I provide a mattress supporting and bed bracing frame comprising parallel longitudinal bars 9 which are connected by cross bars 10 and 11, the bars 10 being attached to the ends of the bars 9 and the cross bar 11 at the center of the bars 9. The bars 9 preferably overlie these cross bars which at each end are provided with a bracing and clamping loop formed by bending the end of the bar upright to form the brace and inner clamp member 12 and then over and down to form the outer clamp member 13. This brace and clamp is provided at each end of each cross bar and as all cross bars are of the

same length I thus provide a light rectangular bracing and clamping frame which is adapted to be applied by forcing its downwardly opening clamp jaws 12, 13 over the 5 side bars 7 of the bed and when this is done the inner brace walls 12 of the clamps will effectively brace the bed in its true rectangular position while the clamp members 12 and 13 of the clamp jaws will so tightly engage 10 the side bars as to hold them and the mattress supporting frame in non-rattling assembled position. The result is that the bed when set up is rigid, strong and has no tendency to rattle. The bed being free of 15 loose parts or any parts requiring the use of a tool to put it up or take it down, represents great simplicity in construction, can be economically manufactured, and will prove very strong and durable in service.

20 Having thus described my invention, but without intending to limit myself to the specific details of construction shown, what I claim, is:—

A toy bed comprising head and foot mem-

bers, each embodying upright side posts, a 25 top cross connecting bar, and lower cross connecting bars slightly spaced, with the ends of all cross bars immovably connected to the side posts, flat sheet metal side bars extending between the side posts at opposite sides of the bed and having their ends bent into loop formations for rotatable mounting upon the side posts between adjacent ends of the lower cross connecting bars with the bars preventing perpendicular 30 movements of the side bars relative to the side posts, and a mattress supporting frame embodying end cross strips of flat sheet metal having their transverse axes extending longitudinally of the bed with the ends of the 35 cross strips bent to inverted U-shape formation for mounting upon the sheet metal side bars to hold the bed frame in rectangular formation.

In testimony whereof I affix my signature. 45
WILLIAM H. STOREY.

Witness:

NOMIE WELSH.
